UNITED STATES PATENT OFFICE.

EDWARD CRAIG, OF ST. JOSEPH, MICHIGAN.

WIREBOUND-BOX CONSTRUCTION.

Application filed May 31, 1921. Serial No. 474,023.

To all whom it may concern:

Be it known that I, EDWARD CRAIG, a citizen of the United States, and a resident of St. Joseph, Berrien County, Michigan, have 5 invented a certain new and useful Improvement in Wirebound-Box Constructions, of which the following is a specification.

This invention relates to wire bound boxes, and the manufacture thereof, boxes 10 of this kind being ordinarily provided with side walls and end walls, and with binding wires extending around the box to increase the strength thereof.

Generally stated, the object of the invention 15 is to provide an improved construction and arrangement whereby additional wires are provided, extending crosswise of the wires which are ordinarily provided to flexibly connect together the sections of the blank 20 which, when folded around the end walls, provide the front and rear sides and the top and bottom of the box.

It is also an object to provide certain details and features of construction and combinations 25 tending to increase the general efficiency and the desirability of a wire bound box of this particular character.

To these and other useful ends the invention consists in matters hereinafter set 30 forth and claimed and shown in the accompanying drawings in which—

Figure 1 is a perspective showing the operation of folding the blank around the heads or end walls, in the construction of a wire 35 bound box involving the principles of the invention.

Figure 2 is a perspective of said box showing the same closed and showing the ends of the wires twisted together to tighten them 40 around the box.

Figure 3 is a plan of the blank, showing the appearance of the same before the additional wires are secured thereto.

Figure 4 is a similar view showing the extra 45 or additional wires applied to the blank.

Figure 5 is a fragmentary perspective view showing the cleat construction of the blank.

As thus illustrated, the blank employed in 50 constructing a wire bound box in accordance with the invention, comprises the four sections 1, 2, 3, and 4 flexibly connected together by the parallel binding wires 5 and 6, these wires being secured in place by staples 7, 55 and the staples for the wires 5 extending

through the veneer or other sheet material from which the sections are made and into the cleats 8 on the inner surface of the blank, whereby the wires are secured to the outer surface of the blank to extend around the 60 box and have their opposite ends twisted together. As shown in Figure 1, the said blank is folded around the heads or end walls 9, in the usual manner, and the said heads or end walls are secured in place in 65 any suitable or desired manner, leaving one section of the blank loose to form the top or cover of the box, so that the latter may be filled. In accordance with the invention, however, additional wires 10 are applied to 70 the outer surface of the blank, at right angles to the wires 5 and 6, and these wires 10 are secured in place by staples 11, or in any suitable or desired manner. The ends of the wires 10, like the ends of the wires 5 and 6, 75 project from the edges of the blank. When the blank is folded around the heads or end walls 9, the wires 10 are twisted together at the outer surfaces of the heads or end walls, where they cross each other at right angles as 80 shown in Figure 2, thus co-operating with the wires 5 and 6 to render the box very strong and to make it capable of withstanding strains which the ordinary wire bound box is not adapted to sustain. 85

While the invention is shown and described in connection with a wire bound box in which the sections of the blank are entirely separate and connected together only by the binding wires, it is obvious that the 90 invention is not limited to the exact construction shown and described.

While the opposite ends of each wire 5 and 6, in the construction of the box, and after the box is filled, are twisted together, 95 it will be seen that, with the exception of the wires 10 which are applied to each horizontal section of the box, the opposite ends of each wire 10, at least those on the front and rear sides of the box, 100 are connected to the opposite ends of a similar wire before the box is filled, if this is necessary or desirable. It is also obvious, however, that the ends of all of the wires 10 can be left free and untwisted until after 105 the box is filled. In any event, the ends of the wires 10 are adapted to be twisted together across the face of each head or end wall 9, and thus the wires 10 not only cross each other, but also cross the wires 5 and 6 110

which have their ends twisted together to tighten them around the box after the latter is filled and closed.

It will be seen that countersunk heads are provided for the box, when the blanks are folded around the head or end wall 9, so that space is afforded for twisting the ends of the wires together at the ends of the box, each twist occurring a distance from the surface of the head or end wall 9 which is set inside of the cleats 8 when the box is completed.

What I claim as my invention is:

1. In a wire bound box, side walls and countersunk end walls forming heads and wires secured to the side walls and crossing each other a distance from the outer surface of each end wall, with a separable twisted connection in each wire opposite each head.

2. In a wire bound box, side walls and end walls forming heads, and wires extending across the end walls and over sides of the box, said wires being attached on the sides but unattached on the ends of the box, with a separable twisted connection in each wire opposite each head.

3. A structure as specified in claim 1, in combination with other wires extending around the box at right angles to said first mentioned wires.

4. A structure as specified in claim 2, in combination with other wires extending around the sides of the box.

5. A blank for a wire bound box comprising sections flexibly connected together by wires, and other wires extending at right angles to said first mentioned wires, with the ends of each wire projecting from the edge of the blank, whereby the ends of the wires may be twisted together on the box.

6. In a wire bound box, side walls and end walls, and wires extending around the box and each having its opposite ends twisted to the ends of another wire at the outer surface of each of said end walls.

7. The process of making a wire bound box, comprising the wiring together of sheet material to provide flexibly connected side walls for the box, attaching other wires over and crosswise of said first mentioned wires, folding the side walls around end walls, and twisting together the ends of said wires. 50

8. The improved wire bound box, comprising one-piece wire extending circumferentially around the box and attached to the sides thereof, and two-piece wires extending over the sides and across the ends of the box, with the sections of each two-piece wire twisted together at each end of the box, substantially as shown and described. 55

9. A structure as specified in claim 5, and cleats secured to the blank to form part of the ends of the box.

10. A structure as specified in claim 1, 60 said wires having ends which are twisted together a distance from the surface of each end of the box.

11. A process as specified in claim 7, including the attaching of cleats during the 65 wiring together of the sides of the box in blank form, and attaching the end walls to said cleats.

12. A box blank comprising flexibly connected sections to form the lateral and upper 70 and lower sides of the box, and one or more wires on each section, extending parallel with the meeting edges of the sections, with the opposite ends of each wire projecting a distance from the edges of the blank. 75

13. A structure as specified in claim 12, and cleats secured along the edges of the blank to form the ends of the box when the blank is folded.

14. A structure as specified in claim 12, 80 and end walls affording space for the ends of said wires to be twisted together when the blank is folded.

EDWARD CRAIG.
